Primary Examiner — Susan Bennett Hattan*Assistant Examiner* — Suzanne E Tisdell(74) *Attorney, Agent, or Firm* — Dority & Manning, P.A.(57) **CLAIM**

The ornamental design for a power transmission coupling, as shown and described.

DESCRIPTION

FIG. 1 is a front perspective view of a power transmission coupling;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along the line 8-8 in FIG. 6; and,

FIG. 9 is a cross-sectional view thereof taken along the line 9-9 in FIG. 4.
